DESIGN FOR A SHOE

Gennaro Del Re, New York, N. Y.

Application May 20, 1935, Serial No. 56,932

Term of patent 3½ years

To whom it may concern:

Be it known that I, Gennaro Del Re, a citizen of the United States of America, residing in Borough of Manhattan, city, county, and State of New York, have invented a new, original, and ornamental Design for a Shoe, for which the following is a specification, reference being had to the accompanying drawing, forming part hereof, wherein,

I claim:

The ornamental design for a shoe substantially as shown.

GENNARO DEL RE.
